UNITED STATES PATENT OFFICE

2,015,971

ASH DUST ELIMINATOR

George Z. Sill, Philadelphia, Pa.

Application February 17, 1933, Serial No. 657,181

1 Claim. (Cl. 126—242)

My invention relates to new and useful improvements in an ash dust eliminator, and has for one of its objects to provide an exceedingly simple and effective device of this character which 5 will be light in weight whereby it may be readily handled in placing the same upon an ash receptacle or when it becomes necessary to remove the receptacle after the same has been filled with ashes.

10 Another object of the invention is to improve the construction of devices of this kind whereby the eliminator may remain in place on a receptacle in proximity to a heating appliance during the time any ashes may be dumped into the receptacle and the connection between the eliminator and the heating appliance being easily and quickly made during the time ashes are being removed from said heating appliance.

Another object of the invention is to provide 20 means for forming a draft directly above the clinker and ash pit doors for taking away any flying ash dust while the ashes are being removed or the fire bed is being raked.

Another object of the invention is to provide an 25 ash dust eliminator comprising a body having a flange and rim to encircle the upper part of an ash receptacle, which body has a valve controlled chute leading thereto with a cone shaped top mounted on the upper end of the body and terminating in a circular outlet at the apex on which is rotatably mounted a conduit comprising a plurality of elbow sections, said conduit adapted to be swung about so that its free or outlet end will project into the fire-door of the heating appliance or assume a position away from the fire door to permit unobstructed access to the latter.

Another object of the invention is to provide means which will support the eliminator on different sized ash receptacles.

40 A further object of the invention is to provide, in combination with the eliminator, a hood of unique construction which will overlie the clinker and ash pit doorways when the eliminator is in operative position.

45 A still further object of the invention is to provide a hanger for connecting the outlet conduit of the hood with the eliminator conduit which will permit adjustments of the eliminator conduit and the hood relative thereto.

50 With these and other ends in view, this invention consists in the details of construction and combination of elements hereinafter set forth and then specifically designated by the claims.

In order that those skilled in the art to which 55 this invention appertains may understand how

to make and use the same, I will describe its construction in detail referring by numerals to the accompanying drawing forming a part of this application, in which:—

Fig. 1 is a plan view of an ash dust eliminator 5 constructed in accordance with my invention and shown in its association with a heating appliance which is conventionally illustrated.

Fig. 2 is a front elevation of Fig. 1.

Fig. 3 is an enlarged vertical sectional view of 10 the eliminator per se.

Fig. 4 is an end view of the hanger for connecting the hood with the eliminator conduit.

Fig. 5 is a top view thereof.

Fig. 6 is a lower end view of the hood.

15

In carrying out my invention as herein embodied, 10 represents any coal burning heating appliance herein conventionally illustrated and shown as provided with a smoke outlet pipe 11, a fire-doorway 12 which is closed by a door 13, 20 a clinker doorway normally closed by the door 14 and an ash pit doorway 15 normally closed by the door 16. For purposes of illustration, a shaker bar 17 is also shown which is used for shaking the grate of the heating appliance to dislodge 25 ashes or other heavy products of combustion.

An ash receptacle 18 is shown as situated in close proximity to the heating appliance and on top of this is mounted the ash dust eliminator 19 embodying my invention, and preferably comprising 30 a body 20 having straight vertical sides, although the body otherwise may be of any desirable contour, but preferably circular as illustrated. From the lower edge of the body extends an outwardly projecting flange 21 adapted to rest on 35 top of the ash receptacle 18 and about the outer edge of the flange is a downturned rim 22 which will surround the upper end of the ash receptacle and prevent accidental displacement of the eliminator from the receptacle.

40 From the upper end of the body 20 extends the cone shaped top 23 terminating at the apex in a circular outlet or neck 24.

In the body of the eliminator is mounted an inclined chute 25 which slants downwardly and 45 inwardly, and should be of sufficient dimensions to permit the insertion of a fire shovel.

Preferably the inner end of said chute 25 extends into the interior of the body and is beveled or of angular formation so that the lower 50 portion of the chute is spaced from the adjacent wall of the body a greater distance than the upper portion of said chute, and said inner end of the chute is normally closed by a hinged gravity actuated valve or closure 26.

55

On the neck 24 is rotatably mounted the eliminator conduit 27 made up of any desirable number of sections 28, 29 and 30, each section preferably being an elbow, but if necessary, 5 straight sections of pipe may be added. The sections of the conduit are rotatably and longitudinally adjustable whereby the parts may be positioned to permit the free end of the conduit to enter straight into the fire doorway 12 when 10 the conduit is swung to a position such as suggested in Figs. 1 and 2. With the conduit in this position, the draft through the heating appliance induces a draft through the eliminator and its conduit so that any dust caused by the dumping of ashes through the chute 25 will be drawn 15 upward through the eliminator and conveyed through the conduit into the heating appliance from which they will be carried off through the smoke stack 11 and the chimney with which 20 the smoke stack is connected.

After the ashes have been dumped into the receptacle through the eliminator, the conduit 27 may be swung around out of the way so as not to interfere with access to the fire doorway 25 12 for coaling or other purposes.

In order that the eliminator may be mounted upon and supported by ash receptacles of smaller diameter than the interior diameter of the body of the eliminator, I place a rod 31 across the lower 30 end of the eliminator body which with a portion of the flange 21 will rest upon the upper edge of a smaller receptacle to permit use of the eliminator.

The device being portable, I provide handles 35 39 for lifting and transporting the same.

The straight vertical walls of the body makes the eliminator self cleaning since there are no projections at the lower end of the body to accumulate or collect falling ashes.

Near the extreme free end of the eliminator conduit 27 is mounted a hanger 32 including a pair of rings 33 and 34 suitably joined together with one of them slipped over the end of the conduit 27 so that it can be moved longitudinally 45 or rotated to obtain a desired adjustment, and in the other ring of the hanger is mounted the inturned end 35 of a conduit 36 leading from the upper end of the tapered hood 37, which hood is adjustable relative to the conduit 36 and said conduit is adjustable in the hanger.

The tapered hood has one concave wall 38 so that it will approximately fit the heating appliance. Said hood is open from top to bottom and is adapted to be positioned above the clinker 55 door 14 where the heating appliance is provided

with such a door and above the ash pit doorway 15 with the inturned end 35 of its conduit projecting into the fire-door parallel with the free end of the eliminator conduit 27.

When in use the draft through the heating appliance will create a draft through the hood and its conduit so that any ash dust rising from the raking of the heating appliance or the removal of cinders and ashes through the clinker doorway or through the ash pit doorway will 10 be caused to float toward and into the hood and be carried off in the same manner as the dust from the ash receptacle. This will prevent ash dust from flying about and finally accumulating on objects in the apartment where the heating 15 appliance is located and will also prevent the ash dust from being drawn through the hot air pipes or passing through cracks in the floors to the living quarters.

Of course I do not wish to be limited to the 20 exact details of construction herein shown and described as these may be varied within the limits of the appended claim without departing from the spirit of my invention.

Having thus fully described my invention, what 25 I claim as new and useful is:—

In a device of the character described, a body having an open lower end for temporary mounting upon an ash receptacle located adjacent a coal burning heating appliance, a cone shaped 30 top on the upper end of said body, a neck projecting upwardly from the apex of said top, an elbow conduit section rotatably mounted on said neck, a second elbow conduit section telescopically and rotatably mounted on the first named section, 35 a third elbow conduit section telescopically and rotatably mounted on the second named section, all of said sections producing a conduit the outer free end of which is rotatable in a horizontal plane for movement into and out of the fire 40 doorway of the heating appliance without shifting the ash receptacle or moving the body relative to said receptacle, a chute carried by said body leading to the interior thereof, a hanger adjustably mounted on the free end of the conduit, a tapered hood having a concave wall to fit against the wall of the heating appliance above the clinker or ash pit door, and a conduit leading from the top of the hood and having a right angle upper end adjustably mounted in 50 the hanger whereby said hood is supported with the balance of the apparatus on the ash receptacle with the outlet ends of both conduits in parallelism.

GEORGE Z. SILL. 55
